UNITED STATES PATENT OFFICE.

ELMER W. HOFFMAN, OF TULSA, OKLAHOMA.

AMALGAMATOR.

1,150,191.

Specification of Letters Patent. Patented Aug. 17, 1915.

Application filed October 28, 1914. Serial No. 869,110.

To all whom it may concern:

Be it known that I, ELMER W. HOFFMAN, a citizen of the United States, residing at Tulsa, in the county of Tulsa and State of Oklahoma, have invented certain new and useful Improvements in Amalgamators, of which the following is a specification, reference being had to the accompanying drawings.

10 This invention relates to certain improvements in amalgamators and has relation more particularly to a device of this general character for use in the separation of gold from the auriferous matter in which it is contained; and the object of the invention is to provide a novel and improved amalgamator whereby the capacity of the machine is materially increased and whereby the auriferous matter is passed slowly 15 through the mercury whereby flouring of the mercury is substantially entirely obviated.

The invention consists in the details of construction and in the combination and arrangement of the several parts of my improved amalgamator whereby certain important advantages are attained and the device is rendered simpler, less expensive and otherwise more convenient and advantageous 20 for use, all as will be hereinafter more fully set forth.

The novel features of the invention will be carefully defined in the appended claim.

In order that my invention may be the better understood, I will now proceed to describe the same with reference to the accompanying drawings, wherein—

Figure 1 is a fragmentary view in side elevation illustrating an amalgamator constructed in accordance with an embodiment of my invention; Fig. 2 is a sectional view taken substantially on the line 2—2 of Fig. 1; Fig. 3 is a view, partly in top plan and partly in section, of the amalgamator as herein embodied; Fig. 4 is a sectional view taken substantially on the line 4—4 of Fig. 3; and Fig. 5 is an enlarged transverse sectional view taken through one of the mixers herein embodied.

0 As disclosed in the accompanying drawings, 1 denotes a trough or well of predetermined configuration adapted to contain the mercury M, the discharge end 2 of the well or trough having its upper edge terminating substantially flush with the level of the mercury, as is believed to be clearly shown in

the accompanying drawings, and leading from such upper edge of the discharge end of the trough or well 2 is the discharge chute 3 disposed on a predetermined incline and over which the waste is adapted to be discharged.

The auriferous matter is delivered upon the mercury at a point adjacent the end opposite the discharge end of the well through a chute 4 or the like and is taken through the mercury M under the influence of the blades 5 radiating from the core 6 mounted upon the shaft 7 disposed transversely of the well or trough and operatively supported thereby. It is to be observed that the core 6 is so mounted as to have the under portion of the periphery thereof substantially flush with the top or level of the mercury M. Each of the blades 5, as herein embodied, has its inner longitudinal marginal portion positioned within a slot 8 produced longitudinally of the core and coacting with such inner longitudinal marginal portion of the blade are the clamping members 9 suitably threaded through the core whereby it will be perceived that the blade 5 may be readily and conveniently adjusted relatively to the core 4, as the requirements of practice may dictate.

One extremity of the shaft 7 projects beyond one side of the trough or well 1 and has affixed thereto the sprocket wheel 10 adapted to be employed in any desired manner with a suitable source of power, as indicated by the conventional sprocket chain 11. Although I have herein disclosed the driving means for the shaft 7 as a chain and sprocket, I do not wish to be understood as limiting myself in this respect as any other driving means may be employed which will operate with convenience and facility.

The shaft 7 is adapted to be rotated slowly in a direction toward the receiving end of the well or trough so that the blades 5 thereof may take the auriferous matter through the mercury without churning or whipping the mercury. In practice I have found that eight or ten revolutions of the shaft 7 per minute results in a maximum of efficiency. As herein disclosed, I position closely adjacent the core 6 a second core 12 rotatably supported by the well or trough 1 with the under portion of the periphery thereof also substantially flush with the top line or level of the mercury M and provided with the blades 14 mounted in the same man-

ner as has been set forth relative to the blades 5. It is to be observed that the core 12 is so positioned relative to the core 6 as to permit the blades 14 thereof to catch the 5 auriferous matter carried through the mercury by the blades 5 and to again take such matter through the mercury. It is to be observed that the core 12 is mounted upon a shaft 7^a and that the shafts 7 and 7^a are 10 operatively connected in order to rotate in unison and in the same general direction through the medium of the endless sprocket chain 23 disposed around conventional sprockets 24 fixed to said shafts 7 and 7^a. 15 While I have herein disclosed but one supplemental core, it is to be observed that any desired number may be employed which will operate with convenience. It might also be well to state that the cores 6 and 12 with 20 their concomitant parts may be termed mixers in accordance with their functions.

Above the discharge end 2 of the trough or well 1 is rotatably supported the transversely disposed shaft 15 provided with the 25 blades 16, the positioning of the shaft relative to the trough or well 1 being such as to permit the free portions of the blades to penetrate the waste matter but not to engage the mercury M. As is believed to be self-evident, upon the proper rotation of the 30 shaft 15, the waste matter will be forced upon the delivery chute 3.

As herein embodied, one extremity of the shaft 15 is provided with a sprocket wheel 35 17 adapted to be coupled with a suitable source of power and, as herein disclosed, has disposed therearound a sprocket chain 18. It is also desirable in practice to have the shaft 7 and the shaft 7^a to rotate in the same 40 general direction and at the same speed. The shaft 15 is adapted to rotate at less speed than the shafts 7 and 7^a and for which reason the gear 17 is of a greater diameter than the gear 10 and the sprockets 24. The 45 chains 11 and 18 are disposed around sprockets 19 suitably affixed to a common shaft 20, said shaft 20 being rotated in any desired manner.

In communication with the bottom of the 50 well or trough 1 at a predetermined point is the draw-off 21 under control of a conventional valve 22, for a purpose which is believed to be obvious.

Copies of this patent may be obtained for five cents each, by addressing the "Commissioner of Patents, Washington, D. C."

From the foregoing description, it is thought to be obvious that an amalgamator 55 constructed in accordance with my invention is of an extremely simple and comparatively inexpensive nature and is particularly well adapted for use by reason of the convenience and facility with which it may be 60 assembled, and it will also be obvious that my invention is susceptible of some change and modification without material departure from the principles and spirit thereof and for this reason I do not wish to be understood as limiting myself to the precise arrangement and formation of the several parts herein shown in carrying out my invention in practice. 65

I claim:

A device of the character described comprising a well adapted to contain mercury, the upper edge of the discharge end of the well terminating substantially flush with the top line or level of the mercury within 75 the well, cores rotatably supported by the well and movable in unison in the same general direction and at the same speed, the under portions of the peripheries of said cores being substantially flush with the top 80 line or level of the mercury, blades radiating from the core, and delivery means depositing upon the upper surface of the mercury at a point in advance of the adjacent core and the blades carried thereby, a rotatable 85 discharge member carried by the well at the discharge end thereof, said discharge member being provided with blades adapted to pass through the waste matter on the mercury, said discharge member being so positioned relative to the upper edge of the discharge end of the well as to prevent the blades thereof from passing into a substantial 90 engagement with the mercury within the well and means for rotating the cores 95 and discharge member in unison and in the same general direction and rotating the discharge member at a reduced speed relative to the cores.

In testimony whereof I hereunto affix my 100 signature in the presence of two witnesses.

ELMER W. HOFFMAN.
